CLAIM

We claim the ornamental design for a clip assembly, substantially as shown and described.

DESCRIPTION

FIG. 1 is a front isometric view of a clip assembly of the present invention;

FIG. 2 is a right side elevation view of the clip assembly of FIG. 1;

FIG. 3 is a top plan view of the clip assembly of FIG. 1; FIG. 4 is a bottom plan view of the clip assembly of FIG. 1; and,

FIG. 5 is a rear end elevation view of the clip assembly of FIG. 1; where the left side elevation view is a mirror image of the right side elevation view of FIG. 2 and the front end elevation view is a mirror image of the rear end elevation view of FIG. 5.

The clip assembly is shown broken away in the middle to indicate that it has no particular length beyond what is shown.
